UNITED STATES PATENT OFFICE.

JOHN E. CHALMAN, OF CHICAGO, ILLINOIS, ASSIGNOR TO UNION SPECIAL MACHINE COMPANY, OF CHICAGO, ILLINOIS, A CORPORATION OF ILLINOIS.

FOLDING DEVICE FOR SEWING-MACHINES.

1,222,069.

Specification of Letters Patent. Patented Apr. 10, 1917.

Application filed May 1, 1913. Serial No. 764,918.

To all whom it may concern:

Be it known that I, JOHN E. CHALMAN, a citizen of the United States, residing at Chicago, in the county of Cook, State of Illinois, have invented certain new and useful Improvements in Folding Devices for Sewing-Machines, of which the following is a description, reference being had to the accompanying drawing and to the figures 10 of reference marked thereon.

My invention relates to folding devices for use in connection with sewing machines, the object of the invention being to provide a folding device for folding and guiding to the stitching mechanism of a sewing machine, a single piece center plait used especially on workingmen's shirts.

As heretofore constructed, the folding device folds a piece of goods and turns in the raw edges, the body of the goods extending into the center plait far enough to be stitched by two of the needles, the upper turned edge of the center plait extending beyond the line of the lower turned edge.

It has been found desirable to reinforce this center plait by an interlining strip inserted beneath the fold of the fabric, and the particular object of the present invention is to provide a folding device which 20 will form the center plait and simultaneously guide an interlining strip therein.

The invention, therefore, consists in the matters hereinafter described and referred to in the appended claims.

The invention is illustrated in the accompanying drawings, in which,—

Figure 1 is a side view slightly in perspective of a folder constructed in accordance with my invention;

Fig. 2 is a plan view of the same, showing the material in place;

Fig. 3 is an edge view;

Fig. 4 is a vertical front view;

Fig. 5 is a vertical sectional view on line 40 5—5 of Fig. 1;

Fig. 6 is a detached top view;

Fig. 7 is a longitudinal section taken on the line 7—7 through Fig. 3; and

Fig. 8 is a sectional view of a center plait 50 with interlining strip.

In these drawings, 1 represents as a whole the folder formed at its receiving end 2 to take in the strip to form the center plait, and gradually tapering toward its delivery end 55 3 to receive in the recess between its outer

and inner walls the edge of the body fabric, and formed as shown to fold in the raw edges of the strip, the edge of the outer wall projecting beyond the edge of the inner wall, thus forming a curved recess 17, the 60 upper portion of which 17' overlies the lower 17. The forwardly projecting upper and lower plates 4 and 5 attached to the inner wall extend beyond the end of the folder and maintain the folds in the upper and 65 lower edges of the center plait strip, while the forwardly projecting side tongues 6 and 7 attached to the walls of the upper and lower recesses serve to guide the folded material in a straight line after it leaves the 70 folder, to prevent the plait itself from widening out between the folder and the needles.

As herein shown, the sewing mechanism includes four needles 8 arranged in pairs, the 75 extreme left hand needle passing through the upper layer of the center plait and the body fabric, the other left hand needle passing through both folds of the center plait, the body fabric and the interlining strip 9, 80 and the two right hand needles passing through both layers of the center plait and the interlining strip.

To guide the interlining strip 9 in proper relation to the layers of the plait, requires 85 a special construction of folder.

As shown in the drawing, the interlining strip is fed from the lower edge of the folder into the guiding slot 10, formed by the plate 11 attached to the inside of the 90 folder.

It passes underneath and then over a wire 12, arranged at an inclination to the axis of the folder corresponding to the inclined mouth of the slot 10. This wire inverts the 95 strip forming an inverting guide therefor, and it is guided along the inner face of the folder beneath the inner wall of the folder 13, and up through a slot 14 in the wall of the folder into the recess 17, which guides 100 and folds the center plait strip, passing out of the delivery end of the folder in contact with the upper layer of the center plait strip, and being guided over the projecting plate 4 and beneath the wire tongue 16. 105

Having thus described my invention, what I claim as new and desire to secure by Letters Patent, is:—

1. A folding guide including outer and inner spaced guiding walls forming a recess 110

- between them for guiding and folding a strip, the inner wall having an opening therein through which a lining strip may be carried into the recess and guided between the upper and lower faces of the folded strip. 5
2. A folding guide including outer and inner spaced guiding walls forming a recess between them for guiding and folding a strip, the inner wall having an opening 10 therein through which a lining strip may be carried into the recess, and having at its delivery end a guiding tongue beneath which the lining strip is guided on its way to the needles. 15
3. A folding guide including outer and inner spaced guiding walls forming a recess between them for guiding and folding a strip, the inner wall having an opening 20 therein through which a lining strip may be carried into said recess, an inverting guide attached to the outer face of the inner wall for guiding and inverting the lining strip. 25
4. A folding guide including spaced guiding walls forming a recess between them for guiding and folding a strip, the inner wall having an opening therein through which a lining strip may be carried into said recess, an inverting guide attached to the outer face 30 of the inner wall for guiding and inverting the lining strip, and a guide for the strip attached to the outer face of the inner wall
- between the edge thereof and the inverting guide. 5. A folding guide including spaced guiding walls, said guiding walls tapering toward the delivery end to form upper and lower walls with a recess between for the passage of the body fabric, a second guiding device arranged at a right angle to the first 35 named guiding recess, and an inverting device for the strip which passes through the right angle guiding device, said inverting device being located to guide the strip above the body fabric in its passage through the 40 folding guide. 45
6. A folding guide including spaced guiding walls forming a recess between them for guiding and folding a strip, a second guiding device arranged at a right angle to the first 45 named guiding recess, means to invert the strip passing through the second guiding device, a third guiding device arranged parallel with the second guiding device, whereby the strip passing through the second guiding device can be passed into the first guiding device. 50
- 55
- In testimony whereof, I affix my signature in the presence of two witnesses.
- JOHN E. CHALMAN.
